UNITED STATES PATENT OFFICE

121,708

DESIGN FOR AN INSOLE FOR A SHOE

Jack Werman, Brooklyn, N. Y.

Application June 14, 1940, Serial No. 93,006

Term of patent 14 years

To all whom it may concern:

Be it known that I, Jack Werman, a citizen of the United States and resident of Brooklyn, in the county of Kings and State of New York, have invented a new, original, and ornamental Design for an Insole for a Shoe, of which the following is a specification, reference being had to the accompanying drawing, forming part thereof, in which:

The figure is a perspective view of the insole for a shoe showing my new design.

I claim:

The ornamental design for an insole for a shoe, as shown.

JACK WERMAN.
